CLAIM

The ornamental design for a planter container, as shown and described.

DESCRIPTION

FIG. 1 is a top, front, left side perspective view of a planter container showing the new design;

FIG. 2 is a perspective bottom, front and left side view thereof.

FIG. 3 is a front view thereof.

FIG. 4 is a rear view thereof.

FIG. 5 is a left side view thereof.

FIG. 6 is a right side view thereof.

FIG. 7 is top view thereof; and,

FIG. 8 is a bottom view thereof.

The broken lines depict environmental subject matter only and form no part of the claimed design.
